LESTER P. BARLOW, OF STAMFORD, CONNECTICUT.

VAPOR-COOLING SYSTEM FOR INTERNAL-COMBUSTION ENGINES.

Application filed January 20, 1927. Serial No. 162,358.

My invention relates to vapor cooling systems for internal combustion engines.

My invention has for its object to provide in connection with the cylinder jacket and condenser of such a system of means for storing the cooling liquid out of the influence of the heat of the engine and supplying the cooling liquid to the cylinder jacket by means also out of the influence of the heat of the engine.

A further object of the invention is to provide a continuous circulation of cooling liquid independent of the condenser and means for admitting a portion of the liquid so circulated to the cylinder jacket.

A further object of the invention is to provide means for automatically regulating the proportion of the circulated liquid admitted to the cylinder jacket.

20 A further object of the invention is to provide a distributing box adapted to so distribute the cooling liquid supplied to it that the level of liquid in the cylinder jacket will be constant at whatever speed the engine may be driven.

A further object of the invention is to provide a distributing box adapted to prevent return of liquid from a cylinder jacket when the engine is not running.

30 With the above indicated objects and other objects hereinafter explained in view my invention consists in the construction and combination of elements hereinafter described and claimed.

35 Referring to the drawings:

Figure 1 is a side view of the internal combustion engine of an automobile having the cooling apparatus of my present invention applied thereto.

40 Figure 2 is a central, vertical, longitudinal sectional view showing the connection box of my present invention in its preferred form, and

45 Figure 3 is a similar view of a modified form of the connection box.

In the drawings 1 indicates the engine cylinder block of usual construction having a water jacket surrounding the engine cylinders. 2 indicates a steam or vapor dome or vapor chamber above and in communication with the water jacket and preferably extending upward a considerable distance above the cylinder heads. 3 indicates a vertically arranged condenser in communication at its upper end by pipe 4 with the

top of the vapor dome 3. 5 indicates the usual fan driven by belt 6 from the engine shaft 7, arranged within the crank case 8. 9 indicates a make up reservoir or tank in communication by inlet pipe 10 with the lower end of the condenser 3 so as to receive the condensed vapors draining from the condenser. This reservoir or tank is so located as to be out of the influence of heat either radiated or conducted, from the engine and is preferably arranged as shown below the level of the engine and to one side of the crank case. As shown this reservoir will be heated only by the heat carried into it by the condensed vapors from the condenser 3.

The make up reservoir is connected by pipe 11 with the intake of pump 12, preferably as shown, a reciprocating plunger pump operated by eccentric 13 on shaft 14 driven in any usual manner from the engine shaft 7. The discharge of the pump is connected by pipe 15 to opening 16 of distributing box 17. This distributing box is adapted to be made and sold as a separate article. It is provided with flanges 18 for securing it to the wall 19 of the engine cylinder jacket and has an opening 20 leading to opening 21 in the wall of the jacket. The opening 16 for the pipe 15 and the opening 20 are preferably opposite and in line so that cooling liquid forced into the connection box through opening 16 will tend to pass through opening 20 into the water jacket. At any convenient point, preferably above the level of the openings 16 and 20, the connection

50 box is provided with a partition having an opening 22 leading preferably through a chamber 23 to return pipe 24 through outlet opening 25. By arranging outlet 25 above the level of openings 16 and 20 the liquid forced in through opening 16 will tend to flow through opening 20 rather than through opening 25. The opening 22 is a restricted opening, that is, is of less area than the cross sectional area of the interior of the

55 return pipe 24 and is preferably of less area than the openings 16 and 20. In the construction shown in Figure 2, which is the preferred construction, the restricted opening 22 is formed in a disc 26 which is held by a light spring 27 normally against a valve seat 28, having an opening 29 through it of much larger area than opening 22. The disc 26 is guided by rod 30 in tube 31 carried by screw plug 32.

In the use of this preferred construction where the pressure from the pump through pipe 15 and the back pressure of the higher water level in the jacket becomes such that 5 the liquid cannot be taken care of by the opening 20, leading to the water jacket, and by the restricted opening 22, leading to the return pipe, the disc 26 will be lifted against the resistance of spring 27 permitting the 10 excess of liquid to pass to the return pipe 24. The opening 20 leading to the water jacket is provided with a check valve 33 to prevent back flow from the water jacket when the speed of the motor is reduced.

15 While the spring pressed disc 26 and the check valve 33 are desirable, they may be dispensed with as shown in Figure 3, in which the restricted opening 22 is in a fixed partition.

20 The condenser 3 is preferably provided with a vent 34 opening to the atmosphere and the tank or reservoir 9 is also preferably provided with a vent or escape valve 35.

In the operation of my invention the heat 25 of the engine cylinders vaporizes the cooling liquid of the water jacket, the vapor collecting in the vapor space or dome 2 and passes by pipe 4 to the upper end of the condenser 3 which is shown as placed as usual at the 30 front of the automobile, is cooled by the atmospheric currents, and is further cooled by the action of the fan 5. The condensed cooling liquid, which may be water or a mixture of water and alcohol or other mixture of low freezing point, flows by gravity 35 through pipe 10 to this make up reservoir 9 which serves as a sump to collect the condensates and also serves as a supply or make up reservoir from which to draw the 40 liquid necessary to maintain the liquid in the engine jacket at a substantially constant level. The vent 34 of the condenser is open to the atmosphere so that the pressure in the condenser cannot become materially higher 45 than atmospheric.

The make up reservoir 9 is here shown as located below the level of the engine cylinder so as that the condensates from condenser 3 will flow into it by gravity and is 50 also so located so that it will be out of the influence of heat from the engine and will remain cool at all times except for the heat carried by the condensates flowing into it from condenser 3. The particular location 55 of the make up reservoir is not essential so long as it is so located as to be affected as little as possible by heat from the engine, either radiated or conducted.

From the reservoir the cooling liquid is 60 drawn by pump 12 and forced through pipe 15 to the inlet 16 of the distributing box through which more or less of it passes through opening 20 into the water jacket to take the place of the liquid driven off as vapor. The pipe 15 is outside the engine frame 65

and is spaced away from it so that it is practically uninfluenced by the heat of the engine. The cooling liquid thus reaches the connection box and is forced into the engine jacket at the temperature at which the liquid in the tank or reservoir is maintained which is relatively low. In a run of over 200 miles with the atmospheric temperature at 35° F. the temperature of the mixture of water and alcohol in the reservoir taken immediately upon the conclusion of the run was 60° F.

The pump 12 is arranged to be constantly driven from the engine shaft, its speed and consequently the return of liquid discharged through pipe 15, depending upon the speed at which the engine shaft is driven. When the engine is driven at low speed, as when idling, all or a considerable proportion of the liquid forced through pipe 15 by the pump will pass through opening 20 into the jacket. When the engine is running at high speed a considerable portion of the large volume of liquid supplied by the pump will pass through the opening 22, or if the disc 30 is raised from its seat against the force of spring 31, through opening 29 into the return pipe 24. The return pipe 24 and the opening leading to it thus acts as a by-pass. The opening 22 being at a higher 95 level than the openings 16 and 20 as shown and the opening 22 being of less area than the opening 20 into the jacket, the liquid will not flow into the by-pass so long as its passage into the jacket is not checked by 100 back pressure.

While the apparatus of my invention is shown in connection with the engine of an automobile it is to be understood that it may be used in connection with any internal combustion engine whether stationary or moving and it is particularly adapted for use with the engines of aeroplanes or other aircraft.

Having thus described my invention, what I claim is:—

1. In a cooling system for internal combustion engines the combination with a cylinder jacket having a vapor space, of a condenser in communication with said vapor space, a make up reservoir for cooling liquid in communication with the condensers, a distributing box outside the cylinder jacket having an opening therein leading to the cylinder jacket, a pipe leading from the make up reservoir to said distributing box, a pump in circuit with said pipe leading from the make up reservoir to said distributing box and a return pipe leading from said distributing box to the inlet side of the pump.

2. In a cooling system for internal combustion engines in combination with a cylinder jacket having a vapor space connected therewith, of a condenser in communication

with said vapor space, a make up reservoir for cooling liquid in communication with the condenser, a distributing box outside the cylinder jacket having an opening therein leading to the cylinder jacket, a pipe leading from the make up reservoir to said distributing box opening into said distributing box opposite to and in line with the opening from said distributing box into the vapor space, a pump in circuit with said pipe leading from the make up reservoir to said distributing box, and a return pipe leading from said distributing box back to the inlet side of the pump.

15 3. In a cooling system for internal combustion engines in combination with a cylinder jacket having a vapor space connected therewith, a condenser in communication with said vapor space, a make up reservoir for cooling liquid in communication with the condenser, a distributing box outside the cylinder jacket having an opening therein leading to the cylinder jacket, a supply pipe leading from the make up reservoir to said distributing box, and opening into said distributing box opposite to and in line with the opening from said distributing box into the cylinder jacket, a pump in circuit with said supply pipe, and a return pipe leading back to the intake side of the pump from a point in said distributing box above the level of the opening from the box into the jacket.

4. In a cooling system for internal combustion engines in combination with a cylinder jacket having a vapor space connected therewith, a condenser in communication with said vapor space, a make up reservoir for cooling liquid in communication with the condenser, a distributing box outside the cylinder jacket having an opening therein leading to the jacket, a pipe leading from the make up reservoir to said distributing box, a pump in circuit with said pipe leading from the make up reservoir to said distributing box, and a return pipe leading from said distributing box back to the inlet side of the pump, the opening from the distributing box to the return pipe being of less area than the interior of the pipe.

5. In a vapor cooling system for internal combustion engines a cylinder jacket provided with an upward extension to form a vapor space, a distributing box and means carried by said upward extension for supporting the distributing box.

6. In a vapor cooling system for internal combustion engines, the combination with a cylinder jacket having a steam space above the same, of a condenser connected with said space for receiving steam therefrom, a reservoir holding an amount of liquid in excess of that furnished through the condenser, and means connecting the condenser and the reservoir to the jacket for supplying liquids

thereto, said reservoir being so associated with the engine that the temperature of the contents of the reservoir will be effected only by the condensate received from the condenser.

7. In a vapor cooling system for internal combustion engines, the combination with a cylinder jacket having a steam space above the same, of a condenser connected with said space for receiving steam therefrom, a reservoir holding an amount of liquids in excess of that furnished by the condenser, and means connecting the condenser and the reservoir to the jacket for supplying liquids to the jacket from the condenser and the reservoir, the latter and its connections to the jacket and the condenser being so located with reference to the engine that the temperature of the contents of the reservoir will be effected only by the condensate received from the condenser.

8. In a vapor cooling system for internal combustion engines, the combination with a cylinder jacket having a steam space above the same, of a condenser connected with said space for receiving steam therefrom, a reservoir holding an amount of liquids in excess of that furnished by the condenser, and connections from the reservoir to the jacket and condenser, respectively, whereby liquids from both the condenser and the reservoir may be supplied to the jacket, said connections being outside of and spaced away from the engine.

9. In a cooling system for internal combustion engines in combination with a cylinder jacket having a vapor space connected therewith, a condenser in communication with said vapor space, a make up reservoir for cooling liquid in communication with the condenser, a distributing box outside the cylinder jacket having an opening therein leading to the cylinder jacket, a check valve controlling said opening, a supply pipe leading from the make up reservoir to said distributing box, a pump in circuit with said supply pipe, a return pipe leading from said distributing box back to the intake side of the pump, and means in the box providing a restricted by-pass connection between the openings in the box into the jacket and return pipe, respectively.

10. In a vapor cooling system for internal combustion engines, the combination with a cylinder jacket having a steam space above the same, of a distributing box through which cooling liquids are supplied to the jacket, said box having inlet, outlet and overflow openings, the outlet opening communicating the box with the jacket, supply and return pipes connected with the inlet and overflow openings respectively, means in the box providing a variable by-pass connection between the overflow and other openings, and a condenser connected with

the steam space of the jacket and with the circuit provided by the supply and return pipes respectively.

11. In a vapor cooling system for internal combustion engines, the combination with a cylinder jacket having a steam space above the same, of a distributing box through which cooling liquids are supplied to the jacket, said box having inlet, outlet and overflow openings, the outlet opening communicating the box with the jacket, supply and return pipes connected with the inlet and overflow openings respectively, with the inlet opening opposite and in line with the outlet opening to provide an unrestricted passage between them, means in the box providing a by-pass connection between the overflow and the other openings, and a condenser connected with the steam space of the jacket and with the circuit provided by the supply and return pipes, respectively.

12. In a vapor cooling system for internal combustion engines, the combination with a

cylinder jacket having a steam space above the same, of a distributing box through which cooling liquids are supplied to the jacket, said box having inlet, outlet and overflow openings, the outlet opening communicating the box with the jacket, supply and return pipes connected with the inlet and overflow openings respectively, with the inlet opening opposite and in line with the outlet opening to provide an unrestricted passage between them, means in the box providing a normally restricted by-pass opening from said passage to the overflow opening, yielding means permitting the by-pass opening to be enlarged by the increase of cooling liquids in said passage, and a condenser connected with the steam space of the jacket and with the circuit provided by the supply and return pipes, respectively.

In testimony whereof, I hereunto affix my signature.

LESTER P. BARLOW.
